UNITED STATES PATENT OFFICE.

FRANK G. HOGLAND, OF CHICAGO, ILLINOIS, ASSIGNOR TO ILLINOIS SEWING MACHINE COMPANY, OF CHICAGO, ILLINOIS, A CORPORATION OF ILLINOIS.

DESIGN FOR A SEWING-MACHINE CABINET.

SPECIFICATION forming part of Design No. 36,100, dated October 7, 1902.

Application filed July 19, 1902. Serial No. 116,212. Term of patent 7 years.

To all whom it may concern:

Be it known that I, FRANK G. HOGLAND, a citizen of the United States of America, residing at Chicago, in the county of Cook and 5 State of Illinois, have invented and produced a new, original, and ornamental Design for Sewing-Machine Cabinets; and I do hereby declare the following to be a full, clear, and exact description of the same, reference being 10 had to the accompanying drawing, forming a part thereof.

The accompanying drawing is a perspective view of my new design for sewing-machine cabinets.

15 The design consists in a cabinet substantially of the configuration shown. The cabinet comprises the plane ends A,

plain swell-front B, the bas-relief columns C, flanking the swell-front B, the torus-formed drawer-front D, the plane hood-ends E and 20 top F, and the ogee hood-front G.

Having described my invention, what I claim as new, and desire to secure by Letters Patent, is—

The ornamental design for a sewing-machine cabinet herein shown and described. 25

In testimony whereof I have signed my name to this specification in the presence of two subscribing witnesses.

FRANK G. HOGLAND.
